C. C. HANSEN.
LIQUID FUEL BURNER.
APPLICATION FILED APR. 2, 1920.

1,377,479.

Patented May 10, 1921.

by *Charles C. Hansen*

his Atty.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

LIQUID-FUEL BURNER.

1,377,479.

Specification of Letters Patent. Patented May 10, 1921.

Application filed April 2, 1920. Serial No. 370,748.

To all whom it may concern:

Be it known that I, CHARLES C. HANSEN, a citizen of the United States, residing at Easton, in the county of Northampton and

5 State of Pennsylvania, have invented a certain new and useful Improvement in Liquid-Fuel Burners, of which the following is a specification.

This invention relates to liquid fuel burners and particularly to burners of this type used in connection with internal combustion furnaces using hydrocarbon fuel in which compressed air is employed to atomize the liquid.

10 15 The object of the invention is to simplify the construction of burners of this character and to obtain more perfect regulation of the relative flow of air and fuel to produce a combustible mixture of the highest efficiency and economy, the fuel and air regulating means each being independently operable, the flow of either being regulable within its minimum and maximum limits at each stage of adjustment of the other.

20 25 This object, as well as others which will appear, are accomplished by the invention, a practical embodiment of which is described in the following specification and illustrated on the accompanying drawings, forming a part hereof, in which—

Figure 1, shows a longitudinal central section through the burner;

Fig. 2, a section on the line 2—2 of Fig. 1, and

30 35 Fig. 3, is a detail sectional view broken away with the nozzle X in forward position.

In the drawings, A represents the hollow burner casing and B the compressed air supply pipe leading thereto. A fuel conveying pipe C extends through the casing, being secured at one end thereof by means of a bushing D secured in the casing, within which bushing D a feed nut E is freely 40 45 50 rotatable by means of a hand wheel F at its outer end. The feed nut E is internally threaded as shown at f and surrounds the fuel conveying pipe C, the surface of this pipe being correspondingly threaded for a portion of its length. A securing nut G screwed on the inner end of the feed nut E bearing against the inner end of the bushing D secures the feed nut E in place in a ro-

tatable condition. Rotation of the feed nut E by means of the hand wheel F will impart a longitudinal movement to the fuel conveying pipe C.

55 60 65 70 75 A valve casing H is interposed between the fuel conveying pipe C and the fuel supply main J and a needle valve K mounted in this casing, projects through the conveying pipe C, being manually operated by means of the hand wheel L to regulate the volume of liquid fuel passing through the conveying pipe C in the manner which will be later set forth. One end of the valve casing H is conveniently secured to the conveying pipe C by any suitable means as a double threaded hollow nut O. A bushing P secured in the opposite end of the casing H is internally threaded to fit threaded portion Q of the needle valve K, the needle valve being thereby movable longitudinally in the pipe C. A stuffing box R is formed in the bushing P and packing S around the needle valve K secured by a gland T maintains a fluid tight connection around the needle valve K.

80 85 90 At the other end of the casing A a cylindrical open ended cap U is threaded, this cap being provided with a discharge opening V at its outer end. The outer walls of the cap U preferably converge slightly toward the discharge end and commingling chamber W is formed within the same, the purpose of which will be presently described.

95 100 105 A nozzle member X is suitably fastened on the end of the conveying pipe C within the cap U by means of screw threads. The nozzle member X is provided with a plurality of radial ribs Y which engage the inner wall of the cap U and, as will be seen, it is thus arranged to slide within the cap as the conveying pipe C is moved longitudinally. A central conical orifice Z is provided at the forward end of the nozzle X through which the liquid fuel supplied from the conveying pipe C exudes. The end of the needle valve K projects into a chamber a in the nozzle X the point of the valve entering an axial port b in the end of the nozzle. Longitudinal movement of the needle valve K by means of the hand wheel L is effected independently of the fuel conveying pipe C and regulates the passage

of the fuel through the nozzle X. A plurality of grooves *d* of which there may be as many as desired in the surface of the needle valve K permit the passage of the 5 fuel from the pipe C to the small chamber *a* at the end thereof.

The construction of the burner is compact and extremely simple, unscrewing of the bushings D and P permitting the ready 10 removal of all the internal parts for cleaning when necessary and for adjustment of the nozzle.

In the operation of the device, compressed air admitted to the casing from the inlet B 15 surrounds the fuel conveying pipe C during its passage and travels through the interstices between the ribs Y and past the nozzle X, being divided into a plurality of streams by these ribs. The streams of air 20 under high velocity due to the contracted area of the opening between the nozzle X and the cap U as shown in the position of the parts in Fig. 3, converge directly at the forward end of the commingling chamber 25 and entrain the liquid fuel exuding from the orifice Z, the air and fuel being thoroughly commingled and atomized in the chamber so that substantially complete oxygenation is obtained, and the mixture is 30 discharged through the opening V into the combustion chamber of the furnace (not shown) where complete combustion takes place. The burner is economical in the consumption of fuel and air and a high degree 35 of efficiency is therefore obtained.

The proportionate amount of air admitted to the commingling chamber is controlled by longitudinal movement of the 40 nozzle X effected by manipulation of the hand wheel F, the longitudinal movement of the nozzle altering the distance between the nozzle X and the end of the cap U at the discharge opening V. The proportionate amount of fuel admitted past the nozzle X into the commingling chamber W is 45 controlled by adjustment of the needle valve K. The variation in the proportion of air serves to maintain a proper quantitative relation between the fuel and compressed air 50 at all times, the quality and degree of atomization and combustibility of the mixture being determined by the movement of the fuel pipe and nozzle with respect to the cap, and the regulation of the flow of fuel effected 55 by operation of the needle valve. The burner is both a high and low pressure burner, because a wide range of the adjustment may be effected suitable for any pressure. 60

Having thus described my invention, what I claim and desire to secure by Letters Patent is:

1. A liquid fuel burner comprising in 65 combination a hollow burner casing having

a supply inlet for air under pressure and an open discharge end of smaller diameter than the body portion of said casing, a longitudinally immovable feed nut revolvably secured in the opposite end of said casing, a 70 non-rotatable fuel conveying pipe extending through said feed nut into said burner casing and operatively connected to be adjusted longitudinally by the rotation of said feed nut, a removable conically formed nozzle member connected to the discharge end of said fuel conveying pipe and centrally guided within said burner casing, a commingling chamber at the forward end of 75 said burner casing formed between the nozzle member and the discharge end of the casing, a plurality of ribs on said nozzle member directly engaging the wall of the burner casing and dividing the air into a plurality of streams, said streams converging directly at said open discharge end of the casing at the forward end of said commingling chamber, a needle valve extending through said fuel pipe to the said nozzle member and guided centrally therein 80 and manual means independent of said feed nut for adjusting said needle valve longitudinally in said fuel pipe and nozzle, said nozzle when in its extreme forward position materially reducing the volume of said 85 commingling chamber.

2. A liquid fuel burner comprising in combination a hollow burner casing having a supply inlet for fluid under pressure and an open outer discharge end of smaller diameter than the body portion of said casing, the walls of the casing converging toward said open end, a bushing removably secured within the opposite end of the burner casing, a rotatable longitudinally immovable feed nut revolvably secured within 100 said bushing, a non-rotatable fuel conveying pipe extending through said feed nut into said burner casing and operatively connected to be adjusted longitudinally by the 105 rotation of said feed nut, a removable conically formed nozzle member screw threaded to the discharge end of said fuel conveying pipe and centrally guided within said burner casing, a commingling chamber at 110 the forward end of said burner casing, formed between the nozzle member and the discharge end of the casing, a plurality of radial ribs on said nozzle member directly engaging the wall of the burner casing and dividing the fluid into a plurality of 115 streams, said streams converging directly at said open discharge end of the casing at the forward end of said commingling chamber, a needle valve extending through said fuel 120 pipe to the said nozzle member and guided centrally therein, said needle valve having a plurality of diametrically opposite longitudinal grooves at the end projecting into the nozzle, and manually operated means in- 125 130

dependent of said feed nut for adjusting said needle valve longitudinally in said fuel pipe and nozzle, said nozzle in its movement being adapted to vary the volume of 5 said commingling chamber whereby the proportions of the combustible mixture are determined by the volume of the commingling

chamber as fixed by movement of the fuel pipe and nozzle with respect to the end of the burner casing.

10

In testimony whereof, I have hereunto set my hand.

CHARLES C. HANSEN.
